UNITED STATES PATENT OFFICE.

GEORGE P. BOSWORTH, OF CENTRAL FALLS, RHODE ISLAND, ASSIGNOR TO HEMPHILL MANUFACTURING CO., OF PAWTUCKET, RHODE ISLAND, A CORPORATION OF RHODE ISLAND.

STOCKING-KNITTING MACHINE, ANTIRAVELING.

1,296,750.

Specification of Letters Patent. Patented Mar. 11, 1919.

Application filed August 31, 1914. Serial No. 859,492.

To all whom it may concern:

Be it known that I, GEORGE P. BOSWORTH, citizen of the United States, residing at Central Falls, county of Providence, Rhode Island, have invented certain new and useful Improvements in Stocking-Knitting Machines, Antiraveling, of which the following is a specification.

One object of my invention is to provide means for producing a course of knitting in a stocking leg to prevent raveling below the point where this course is thrown in, say, about at the top of the calf.

The invention is capable, however, of other uses, and it will be understood therefore that the invention is not limited to the production of the specific fabric mentioned.

My invention, while shown in connection with a hosiery machine of the type known as the "Banner" made under United States Letters Patent of Hemphill, #933,443, September 7, 1909, is not limited to its application to a machine of this make.

The invention is shown in the accompanying drawings in which—

Figure 1 is a developed view of the needle cams, and the needles and jacks.

Fig. 2 illustrates long and short butt needles and a jack, a set of each of which is employed in this machine.

Fig. 3 is a diagrammatic plan view of the machine with the parts set for performing ordinary plain knitting, this view being different from Fig. 1 in this respect in that in Fig. 1 the cams are set to make the special course to prevent raveling.

Fig. 4 is a diagrammatic view showing one of the cams with the connections for automatically adjusting the same and the connections for controlling the yarn feed.

Fig. 5 is a perspective view of the needle lifting cam which is active during heel and toe work.

Fig. 6 is a diagrammatic developed view of the cams and needles showing another form of my invention in which the jacks are omitted.

Fig. 7 shows the needles as used in this modification.

Fig. 8 is a view of part of a needle cylinder with a needle cam and one of the long tail needles which coöperate therewith.

Fig. 9 is a view of the stocking.

Fig. 10 shows a modification.

Fig. 11 is a detail.

55

Referring to Figs. 1 to 4 inclusive:

In the drawings 1 is the needle cylinder which rotates in the direction of the arrow. The needles are in two sets, one set of long butts *a* and one set of short butts *b*, each set occupying one-half of the needle circle. Narrowing picks are shown at 2, widening picks at 3, stitch cams at 4, 4', upper guard cam at 5, lower central guard cam 5', instep cam at 6, and instep lowering cam at 6', all as in ordinary practice in the machines of the Banner type.

In knitting a stocking on my machine the garter top and the upper part of the leg are made in the ordinary way to the point at 70 or above the calf of the leg at which it is desired to stop raveling should this occur, so that if raveling starts above this point it will be stopped here and prevented from going below this point.

In order to provide a course of knitting at the desired point to arrest or stop raveling, I employ a cam arrangement which will divide the needles, allowing every other needle throughout the needle circle to knit 80 while the other needles are retracted to a low plane and prevented from taking yarn on this round, these last mentioned needles simply holding their stitches during this round, after which these needles are brought 85 into work again and knitting of the ordinary fabric is continued on all the needles to form the stocking in the usual way.

For controlling the needles to make this non-raveling course I divide them just before they reach the thread feed so that only every other needle will rise to take the thread. For this purpose I provide a lowering cam 7 which is shiftable radially in relation to the needle cylinder, and when 95 this is in its innermost position it lies close to the needle cylinder so that all the needles will be lowered from their normal plane, as indicated by the knitting wave at *c*, Fig. 1. For this purpose the cam ring 8 is cut down 100 at 9 so that the needle butts may travel down this incline on the under side of the cam 7. The normal plane of the needle butts is indicated at *d*. I also provide the cam ring 8 with a pivoted section at 10, this 105 being the portion which, by its inclined edge

11 in ordinary practice during reciprocating knitting, serves to return or lift the needles to their normal plane indicated by the character *d*.

5 This section is ordinarily rigid and in one with the cam ring 8, but with my improvement it is formed separately and is pivoted to the main portion of the cam ring at 12. It is under tension of a spring 13 10 tending to hold it in normal position with its incline 11 in the path of the needles.

As shown in Fig. 3, the main body of the cam is inclined in relation to the needle circle, presenting a side at 13° which extends 15 at an inclination to the cam ring 8. The pivot 12 is at the outer end of the cam and out beyond the cam ring 8 and needle butt circle.

The movement of the cam inwardly is 20 limited by a tongue or projection 14 at the point of the cam fitting in a recess in the cam ring, the under side of the tongue being inclined inwardly and upwardly, and the recess in the cam ring being formed to correspond. This construction not only provides a stop, but it also provides a flush joint 25 between the point of the cam and the horizontal upper edge of the cam ring for the unobstructed passage of the needle butts 30 thereover.

Coöperating with the needles are the jacks 15. These have one length of butts. They are placed under every other needle, in the slots of the cylinder, throughout the entire 35 needle circle. These butts slide in a cam groove 16 in the plate 16°. This cam groove has a Δ shaped portion 17 adjacent the pivoted section 10 of the cam ring. The action 40 of the parts is as follows: Supposing the point has been reached in the knitting where it is desired to make the non-raveling course. The inclined radially movable cam 7 is adjusted inwardly one step while the short butt 45 needles are passing it, it being understood that normally this cam is set out beyond the path of the long butts. When the cam is moved inwardly one step it comes against the end faces of the short butt needles and in this position it engages over and lowers 50 the long butt needles when they come around, and owing to the short butts having passed the cam, said cam will take another step inward and will now lower these short butt needles when they come around, and thus 55 all the needles throughout the circle will be lowered by the cam 7 to a point where they would pass the thread feeder A without taking thread. Every other needle, however, 60 throughout the whole needle circle after being lowered as just described is immediately elevated again to its normal plane *e* and this is done by the jacks riding up the cam groove 17 and pushing the needles up, these jacks, as before stated, being under every 65 other needle only. Those needles which are

not raised from their retracted position by jacks simply hold their old loops and pass the thread feeder A without taking thread.

These retired needles pass their butts through the idle needle pathway 18 below the cam set 4, 4', 5 and 5'. All the needles, when lowered by the cam 7, can pass the cam section 10 which, being pivoted as above described, is turned aside by the pressure from the needle butts acting against its side 75 13° which, as above mentioned, is inclined to the path of said butts. The position of this cam section, when thrown aside, is indicated in Fig. 3 in dotted lines. Those alternate needles which are raised by jacks are thereby 80 restored to normal plane and thus they are in position to be further elevated to take the yarn by the advancing incline 4°.

The pivoted cam 10 does not perform any function in the above described action. The 85 outwardly swinging movement which it is given is to remove it from obstructing the free travel onward of the lowered needles, and those which are being raised by the cam groove 17. This cam only acts to elevate 90 needles during reciprocating knitting for making the heel and toe. Therefore, it will be understood that its pivotal mounting is merely for the purpose of allowing it to be pushed aside so that the retired needles and 95 those which have been retired and are now being elevated may pass by it.

It will be observed that in making this non-raveling course alternate needles are operated to knit and the other needles are held 100 retired to miss knitting on this run. These latter needles hold their loops until on the next round they again receive the yarn from the feeder A, and then they cast off.

In removing the cam 7 from operation it 105 is withdrawn step by step. Its first outward step takes place, while it is in engagement with the long butt needles for the second time, it requiring one and a half revolutions of the cylinder to complete the operations above described, though it will be understood that a number of the described non-raveling courses may be knit if desired.

This first step movement is sufficient to 115 position the cam 7 out of line with the short butt needles when they come around, which then remain in normal plane to be advanced by cam 4° for regular knitting, and having remained in this one step position while the long butt needles are passing it, the cam takes another step movement outward as soon as the long butt needles have passed and while the short butt needles are passing the cam unaffected thereby. Its second step 120 movement carries the cam out of the path of the long butt needles, which now, together with the short butt needles, remain in their normal plane for ordinary knitting.

The radially movable cam 7 is operated 125 inwardly by a spring 19, the said cam hav-

ing a shank portion 20 sliding in a bracket 21 secured to the machine frame. The cam is retracted outwardly or away from the path of the needle butts by a lever 22 bearing on a pin 23 secured to the shank, said lever being connected by a rod 24 with a lever 25 pivoted to the frame at 26 and having its end bearing upon the pattern wheel 27 secured to the pattern drum shaft 8' of the Hemphill patent. These connections are under tension of a spring 28 which is stronger than the spring 19 and when free to exert its force will overcome the tension of the spring 19 and keep the cam 7 retracted radially outward.

For setting the cam inwardly the pattern wheel 27 has a long projection 29 which lifts the levers 25 and 22 and allows the spring 19 to act in forcing the cam radially inward. The projection 29 is high enough to remove the lever 22 far enough from the pin 23 to allow the cam movement sufficient to carry it up to the cylinder. Its inward movement, however, is step by step, because it first hits against the end faces of the short butt needles, but as soon as these have passed and the long butts begin to ride under the cam then the spring 19 will complete the inward movement of the cam to get into the path of the short butt needles. In retracting the cam the pattern wheel is moved one step sufficient to cause the lever 25 to drop off of the long pattern projection 29 and to fall onto the shoulder 30. This allows the spring 28 to retract the cam 7 one step, overcoming in this action the force of the spring 19. The pattern wheel now takes another step in the arrow direction and allows the lever 25 to drop off of the shoulder 30, and this permits the spring 28 to move the cam 7 all the way out to lie outside the path of all the needle butts, the lever 25 now resting on the periphery of the pattern wheel.

From the above it will be seen that the cycle of operations respecting the cam 7 is as follows: It is moved in, while the short butt needles are passing it and consequently moves in one step, its movement being limited by coming against the end face of the short butts. When the long butts begin to ride under it, the short butts having passed and no longer obstructing the inward movement of the cam, said cam, under its spring tension, moves all the way in. It remains in long enough to lower all the needles, acting to lower the long butt half circle first and then the short butt half circle. Now, in order to restore the cam to its outward position, it will be seen that it can not be moved outwardly until after all the short butt needles have passed the cam and have been lowered. Before all the short butts have passed the cam 7, however, some of the long butts have started under the cam and have

been lowered so that it is now necessary to lower all of these long butt needles, otherwise they would strike the cam 4 and cause a smash up. The cam, however, is withdrawn half way out so that it will be in position to lower all the long butts, but will be out of the path of the short butts, and when these come around they will remain up in normal plane. As soon as all the long butts have passed the cam it is given another outward step movement so as to get out of the path of these long butts when they come around again. This completes the cycle.

Instead of employing jacks for the needles I may use as shown in Figs. 6, 7 and 8 needles having long tails 31, these being alternated throughout the whole needle circle with needles of ordinary construction, *i. e.*, without these tail portions.

Coöperating with these long-tail needles is the cam 17^x on the inner side of the cam ring 8^x. The needle guide walls of the cylinder are cut away to pass this cam, as shown in Fig. 8.

This cam raises every other needle, *i. e.*, 90 all the long-tail needles so that the same result is secured as in the case of the jacks above described, that is to say, the needles are divided, every alternate needle rising to take the yarn while the other needles remain down and hold their loops and pass the feeder without taking yarn. The other parts of the mechanism remain the same as that first described including the radially movable cam 7 and the pivotally mounted 100 cam 10.

My machine organized as above described is also adapted to drop off the fabric automatically and to start automatically the production of the next stocking. In doing 105 this it is simply necessary to throw the yarn out of work by raising the thread finger A as is well known to knitters, and allow the fabric to run off. The thread is then put in work again by lowering the yarn guide and the cam 7 is adjusted automatically inward to divide the needles so that alternate needles will first take the yarn as a foundation or starting course, the other needles remaining down, and the yarn being floated 110 by them on the inside due to the action of the web holders. On the next course all the needles rise to take the yarn and the formation of stitches then proceeds in the ordinary way. Web holders coöperate with the 115 needles as in ordinary practice, the main difference from ordinary practice being that in starting the formation of the fabric the yarn is fed to alternate elevated needles first on one run, the other needle remaining down, and then to all the needles on the next run, all the needles being advanced on this run.

With my construction and operation as above described the latches will be auto- 120 125 130

matically opened before the needles arrive at the thread feeding point, thus insuring that they will take the yarn. This result is due to the retiring of all the needles by 5 means of the cam 7 just prior to their arrival at the feeding point. After the yarn has been raised from the needles and the fabric has been dropped, the empty needles will pass down beneath the cam 7, this having 10 been adjusted in to start the new fabric as above described, and as the needle butts reach the horizontal surface of the cam ring the impact of said butts against said surface subjects the needle to a jar sufficient to open 15 any latch which may be closed when the needle reaches this point. This result will be aided or supplemented also by the action of the jacks in Fig. 1, and of the cam 17* in Figs. 6, 7 and 8 giving the needles their upward movement, the quick impulse serving 20 to throw any latches down which may be closed or partially closed.

Referring to the relative arrangements of the controlling blocks on the pattern drum 25 for operating the yarn feed and the radially movable cam 7 for dividing the needles for making the starting course, I show diagrammatically in Fig. 4 the yarn finger A down in feeding position. This yarn finger is 30 controlled by a lever 32 as in the ordinary Banner machine, pivoted at 33 and having its rear arm 34 connected by a link 34* to a lifting lever 35 pivoted at 36 and arranged to lift the yarn finger when a block 37 on the 35 drum comes beneath the lever, all as in ordinary practice. This block 37 moves in unison with the blocks 29*, 30*, being carried by the same drum. The relation between the blocks 37 and 29*, 30* and the levers 32 and 40 25 is such that the lever 32 is lifted first, resulting in withdrawing the yarn from the needles by lifting the yarn finger A and immediately after the work has been run off the needles due to thus lifting the yarn 45 finger, the lever 32 falls off the block 37 and places the yarn in work again by lowering the yarn finger A to the position shown in Fig. 4. This takes place before the block 29* comes under the lever 25. Immediately 50 after the yarn is in work again, however, the said block 29* comes beneath the lever 25, raising it, and thus turning the lever 22 into position to allow the spring 19 to move the cam 7 radially inward, with the result 55 that all the needles are retired by the cam 7; their latches are opened by impact of their butts against the horizontal surface of the cam ring, and then alternate needles are elevated either by the jacks or the long 60 tails, so that a starting course of yarn will be laid against these needles, and by the action of the web holders the yarn will be sunk, positioning it so that when the other needles rise the yarn will be on the inside

of the same and thus the formation of 65 stitches will be started.

The cam 7 is withdrawn outwardly to permit all the needles to rise after one and a half revolutions have been made by the lever 25 falling off the block 29* onto the step or 70 shoulder 30* and then from this shoulder onto the periphery of the cam wheel.

In the form shown in Fig. 4 the pattern drum of the invention is shown with two projections 29* and 29 each having a step 75 therein for stepping outwardly the dividing cam 7. The first projection 29* is for making the starting course as above explained after the fabric has been run off. The second projection is for forming the 80 anti-runback course as above explained. I have however provided, as shown in Fig. 10 an arrangement which will make a plurality of successive starting courses so that if a needle or several needles fail to take the yarn 85 on the first round, said needle or needles will take the yarn on the next round and thus the absence of drop stitches will be insured.

This will be referred to more at length 90 later on in this description.

In the form first described, it required a step movement of the pattern drum for each outward or retracting step movement of the cam 7, and these step movements were effected by the spring 28 coöperating with the 95 step projections 29* and 29. This step movement of the pattern drum uses up the pattern drum surface and therefore in the form shown in Fig. 10 I provide means whereby the step movement of the cam 7 in 100 retracting to its outward position is not derived from any movement of the pattern drum in coöperation with a spring such as 28 but is derived through positively operating mechanism which acts while the said pattern 105 drum is at rest. For the latter purpose the lever 25 is lowered step by step independently of any movement of the pattern drum. This lever as in the form shown in Fig. 4 draws the cam 7 back step by step through 110 the rod 24 and lever 22, the spring 28 being omitted. The mechanism for doing this consists of a lever 38 pivoted at 39 to the frame and connected by a link 40 with the lever 25. The lever 38 is operated step by step by 115 an arm 41 on the shaft 42 of the gear segment *i* well known in the Hemphill machine, said segment being the member which reciprocates the needle cylinder during heel and toe work through gearing a part of which 120 is shown at *i* on the shaft *s*. This segment during round knitting continues its oscillation, but idly, because the gearing driven thereby is unclutched from the knitting head during round knitting all as explained in the 125 Hemphill patent. Its movement is utilized, however, to positively operate the lever 25 through the arm 41, lever 38 and link 40,

For this purpose the lever 38 has two step abutments or shoulders 43, 44 against which the arm 41 works on its movement from left to right in Fig. 10. By striking the first 5 abutment 43 the lever 38 is operated to lower the lever 25 one step to retract the cam 7 out of the path of the short butt needles and by the arm 41 continuing its movement after acting against shoulder 43 and striking the 10 second abutment 44, the second downward movement is given to the lever 25 to retract the cam 7 out of the path of the long butt needle. There is a dwell however, between the first and second step movements at which 15 dwell the long butt needles are passing the cam 7 as above explained. This dwell is due to the space 45 existing between the first and second abutments 43 and 44 and while the end of the arm 41 is traversing this space 20 the cam 7 is at rest and half way retracted. When the arm 41 strikes the second abutment 44 the lever 25 is moved down to the full limit of its movement and the cam 7 is thereby retracted out of the path of the 25 long butt needles, and it will be observed that both of these movements of retracting the cam 7 away from the needle butts take place while the pattern drum is at rest so that none of its pattern surface is used up. 30 This movement takes place as the gear segment is moving from right to left, Fig. 10 and while the pawls i^4 and h^8 connected thereto are performing the retracting or idle stroke; these pawls act respectively upon the 35 ratchets c and e of the Hemphill patent and they act on the forward stroke of the gear segment i , e , to the right in Fig. 10. The pawl i^4 acts each time to turn the ratchet wheel c one step and this moves the pattern 40 chain B one step for each forward movement of the segment. The pawl h^8 however which acts on the ratchet e of the pattern drum 27' is controlled to miss the said ratchet at times and to engage the same at other times by 45 a controller h . This controller in turn is controlled by lugs or blocks on the pattern chain B, such lugs or blocks being indicated at 1^x , 2^x . The controller has a projection (dotted lines) at h^4 extending from its lateral face, said projection riding on the lugs 50 of the pattern chain and thus the said controller is lifted. The controller has a tail portion h^7 on which the pawl h^8 is adapted to ride when said tail portion is lifted and 55 when the pawl h^8 rides thereon it will miss the teeth of the ratchet e and therefore the pattern drum will not be given a forward step. The controller is pressed by a spring z . The controller in Fig. 10 is shown as 60 having just fallen off of the lug 1^x of the pattern chain. The pawl h^8 is at the forward limit of its stroke having just finished giving the pattern drum a forward step movement, the tail piece of the controller has been

raised to such position that the pawl h^8 on 65 its next forward stroke will miss the next tooth in the ratchet and the pattern drum will not be moved until another lug on the pattern chain comes to the controller and lifts it. For convenience only a few of the 70 pattern lugs are shown and only a portion of the pattern chain.

The projections on the pattern drum are shown at 29^a , 29^b and 29^c . These act on the lever 25 and raise it to permit the spring 19 75 to force the cam 7 inwardly to make the starting course or the anti-raveling course. The two projections 29^a and 29^b are the ones employed for making a plurality of starting courses, two in the instance shown. While 80 the projection 29^c is the one employed for making the anti-raveling course. When in the revolution of the pattern drum in the direction of the arrow Fig. 10 the projection 29^a raises the lever 25 for the starting course, 85 the cam 7 is set in step by step by the spring 19 as above explained and the starting course is made. The same forward movement of the drum under the action of the pawl h^8 and ratchet which causes the projection 29^a 90 to raise the lever 25 as just mentioned moves the projection slightly past the lever as shown in Fig. 10 in connection with the second projection. This leaves the projection in such position that the lever 25 can be returned step by step to normal low position by the positively operating mechanism as 95 above explained.

After one starting course has been made by the projection 29^a and the lever 25 has 100 been returned together with cam 7 this action is repeated by the second projection 29^b and the parts are shown in Fig. 10 after the second action has been inaugurated the lever 25 being up due to the lifting action of the 105 projection 29^b and the projection being now beyond the end of the lever so that this is free to be moved down step by step by the lever 38, arm 41, and shoulders 43, 44. The projection 29^c later comes into action for the 110 non-raveling course. The lug 1^x on the pattern chain is long enough to hold the controller h out of operation so that the pawl h^8 can act successively in turning the drum to bring first the lug 29^a into action and then 115 the lug or projection 29^b . A friction device of any suitable character may be used to restrain the operation of the movement of the lever 38. This may consist of a spring 120 46 adjusted by a screw 47 passing through the slot 48 in the lever 38 into the frame of the machine.

When the lever 25 is operated by either of the lugs to move the rod 24 up and thus allow the spring 19 to act, the friction device will retain the lever and rod in their moved position. Because of this the pattern drum in making its movement may 125

carry its projection or other operating member past the end of the lever, the lever will not fall but must be restored to normal position by the positively operating mechanism actuated by the quadrant and segment ¹⁵.

An organization similar to that disclosed herein is also shown in my application No. 858,953, filed August 25th, 1914.

I claim as my invention:—

- 10 1. In a stocking knitting machine and in combination, needles, stitch cam means, a restoring cam on each side of said stitch cam means for raising the needle to normal plane, one of said restoring cams being movably mounted to allow needles to pass when raised from retired position, means in advance of said movable restoring cam for retiring the needles from normal plane while holding their loops, and means for raising alternate needles after being retired for clearing their loops below their latches and for taking the yarn, said movable restoring cam moving aside for this action of raising alternate retired needles, the other retired needles passing on in retired position without taking yarn or casting their loops while the alternately raised needles are retracted to cast their loops, substantially as described.
- 15 2. In a stocking knitting machine and in combination, needles, stitch cam means, a restoring cam on each side of said stitch cam means for raising the needles to normal plane, one of said restoring cams being movably mounted to allow retired needles to pass, means in advance of the said movably mounted restoring cam for retiring the needles from normal plane while holding their loops, and means for raising alternate needles after being retired to be advanced for clearing their loops below their latches and for taking the yarn, said movably mounted restoring cam moving aside for the passage of the said alternate needles when advanced from retired position, the other retired needles passing the stitch cam means in retired position without casting their loops, the movement of said movable restoring cam resulting from the pressure from the advancing alternate needles, substantially as described.
- 20 3. In combination in a stocking knitting machine, needles, stitch cam means, needle restoring cams one on each side of said stitch cam means, one of said restoring cams being radially movable to allow the passage of needles which are being advanced from retired position, a needle retiring cam in advance of the said movable restoring cam with means for moving said retiring cam at times to operative position to retire all the needles, and means for raising alternate needles to be advanced for taking the yarn while the other retired needles pass the stitch cam means in said retired position and hold their loops, substantially as described.

4. In a stocking knitting machine and in combination, needles, stitch cam means, a restoring cam on each side of said cam means for raising the needles to normal plane, one of said restoring cams being movably mounted to allow the passage of needles which are raised from retired position, a cam in advance of the movably mounted restoring cam for retiring the needles, and means for raising alternate needles after being retired, for taking the yarn, said movably mounted restoring cam moving aside for the passage of these alternate advancing needles, the other retired needles passing the stitch cam means in retired position without taking yarn or casting their loops, said movable restoring cam being pivotally mounted to swing radially, substantially as described.

5. In combination in a stocking machine, needles, stitch cam means, restoring cams, one on each side of the stitch cam means to raise the needles to normal plane, one of said restoring cams being pivotally mounted and extending with a part of its inner side at an inclination to the path of the needle butts, and a needle retiring cam in advance of the movable restoring cam with means for automatically adjusting said cam to and from operative position, and means for raising alternate retired needles to take the yarn, said pivotally mounted restoring cam moving aside by pressure from the alternate needles, when advanced from retired position, substantially as described.

6. In combination in a stocking knitting machine, needles, stitch cams having a path below the same for the needles, means for dividing the needles as they approach the stitch cam consisting of a needle retiring cam for retiring all the needles and means for advancing alternate retired needles to take the yarn, a movable needle restoring cam, and a yarn feed timed to be thrown into operative position to feed the advanced alternate needles first and then all the needles.

7. In combination in a stocking knitting machine, a yarn feed, means for automatically operating the same to place the yarn into and out of work, stitch cams, a needle retiring cam, in advance of the stitch cams to retire all of the needles and having a contact surface at the lower end of the same against which all the needles will strike and thereby open their latches, means for operating the said cam to retire the needles empty after the yarn feed has been moved out of work, and means for then advancing alternate retired empty needles to take the yarn, substantially as described.

8. In combination in a stocking knitting machine, needles, stitch cam means for performing round or reciprocating knitting, said stitch cam means having a needle path below the same for retired needles, a needle

- retiring cam in advance of the said cam set for retiring all of the needles below their normal plane and means for advancing alternate retired needles to knit while the other retired needles pass the yarn feed without taking yarn and without casting their stitches.
9. In combination, in a knitting machine, a needle cam operating step by step, to and from its innermost position, a pattern drum, connections operated by said pattern drum for operating the needle cam, means for operating the pattern drum having forward and backward movement and operating said drum on its forward movement, said means on its backward movement retracting said cam step by step while the pattern drum is at rest, substantially as described.
10. In combination in a knitting machine, a pattern drum having a projection thereon, a needle cam, connections operated by the said projection for controlling the needle cam, means for operating the drum step by step, and in one step movement to carry the projection first into connection with and then past said connections and means for then retracting the said connections while the drum remains at rest, substantially as described.
11. In combination in a knitting machine, a needle cam, long and short butt needles, a spring for setting the cam inwardly step by step to operate the needles, a pattern drum or member, a connection between the drum and the needle cam for holding it retracted against its spring pressure, said drum having a projection to operate said connection and allow the spring to act, means for operating the drum step by step and in one step movement to carry said projection first into contact with and then past said connection and positively operating means operating while the pattern drum is at rest for returning the said connection step by step to normal position, substantially as described.
12. In combination in a knitting machine, a needle cam, a pattern drum having a projection thereon, a connection operated by said projection for controlling the needle cam, an oscillating segment, pawl and ratchet mechanism between the same and the pattern drum for operating it step by step and means operated from said oscillating segment for retracting the said connection step by step while the pattern drum is at rest.
13. In combination in a knitting machine, a needle cam, a pattern drum having a projection thereon, a connection operated by said projection for controlling the needle cam, an oscillating segment, pawl and ratchet mechanism between the same and the pattern drum for operating it step by step and means operated from said oscillating segment for retracting the said connection step by step while the pattern drum is at rest.
14. In combination in a knitting machine, a needle cam, a pattern drum, connections operated by the pattern drum for setting the cam in operative position, a member having stepped shoulders for operating the said connections step by step back to normal position and means for operating said member while the pattern drum is at rest, substantially as described.
15. In combination in a knitting machine, a needle cam, a pattern drum, connections operated by the pattern drum for setting the needle cam in operative position, an oscillating segment, pawl and ratchet mechanism operated by the segment on its movement in one direction for turning the pattern drum, and means operating on the backward movement of the segment for returning the said connections to normal position substantially as described.
16. In a stocking knitting machine and in combination, needles, a cam set including a pair of stitch and a pair of advancing cams for performing round or reciprocating knitting, a restoring cam on each side of said cam set for raising the needles to normal plane, one of said restoring cams being movably mounted to allow the needles to pass, means for retiring the needles at said movable cam from normal plane while holding their loops and means for raising alternate needles after being retired to be advanced for clearing their loops below their latches and for taking the yarn, the other needles which had been retired passing the said cam set without casting loops while the said alternate raised needles are retracted to cast their loops, substantially as described.
17. In a stocking knitting machine and in combination, needles, a cam set including a pair of stitch and a pair of advancing cams for performing round or reciprocating knitting, a restoring cam on each side of said cam set for raising the needles to normal plane, one of said restoring cams being movably mounted to allow the needles to pass, means for retiring the needles at said movable cam from normal plane while holding their loops and means for raising alternate needles after being retired to be advanced for clearing their loops below their latches and for taking the yarn, the other needles which had been retired passing the said cam set without casting loops while the said alternate raised needles are retracted to cast their loops, said movable restoring cam being moved aside by pressure from the needles.

18. In a stocking knitting machine, in combination, needles, stitch and advancing cams, restoring cams for raising the needles to normal plane, one of said restoring cams being movably mounted to allow the needles to pass, means for retiring the needles at said movable cam and means for raising alternate needles after being retired to be advanced for taking the yarn, the other needles 10 which had been retired passing the needle

cam without casting stitches, said movable restoring cam being pivotally mounted to swing radially.

In testimony whereof I affix my signature in presence of two witnesses.

GEORGE P. BOSWORTH.

Witnesses:

EDITH M. BROMLEY,
JOHN LAWSON.
